UNITED STATES PATENT OFFICE.

LOUIS GODDU, OF WINCHESTER, ASSIGNOR TO JAMES W. BROOKS, TRUSTEE, OF CAMBRIDGE, AND FRANK F. STANLEY, ASSOCIATE TRUSTEE, OF BOSTON, MASSACHUSETTS.

WIRE-NAILING MACHINE.

SPECIFICATION forming part of Letters Patent No. 398,606, dated February 26, 1889.

Application filed April 5, 1888. Serial No. 269,679. (No model.)

To all whom it may concern:

Be it known that I, LOUIS GODDU, of Winchester, county of Middlesex, State of Massachusetts, have invented an Improvement in 5 Machines for Inserting Screw-Threads in Leather-Work, of which the following description, in connection with the accompanying drawings, is a specification, like letters on the drawings representing like parts.

10 This invention relates to machines for inserting screws cut from screw-threaded wire into boots and shoes, it being an improvement upon the machine substantially such as shown and described in United States Reissue Patent No. 7,033, granted to me April 4, 1876.

15 My present invention relates more particularly to the spindle employed to feed the wire to cutters, and has for its object to improve the construction of the same, as will be described, by which durability is imparted to the said spindle.

20 In the machine referred to the wire to be acted upon is fed forward through the spindle by feed-rolls operated by a slide forming part of the said spindle, the said slide being provided with screw-threads which are engaged by a threaded sleeve secured to the said slide by suitable screws, and having loosely mounted on it a collar connected to the mechanism by which the said spindle is reciprocated, the said collar being secured on the threaded sleeve by a nut screwed thereon.

25 In practice the loose collar on the threaded sleeve becomes worn after considerable use by the repeated reciprocations of the slide, thereby giving rise to lost motion between the said collar and sleeve and nut, thus affecting the regularity of the feed.

30 This invention has for one of its objects to take up the wear between the parts referred to; and I accomplish this feature of my invention by providing the nut by which the collar is secured to the sleeve with a series of holes arranged around the periphery of the said nut, so that the said holes are in line with or will follow the pitch of the threads, the said holes in turn registering with a hole in the sleeve, the said nut and sleeve being secured in ad-

justed position by a bolt or screw inserted through the registering holes.

35 Another feature of my invention consists in providing a novel and durable bearing for the journals of the feed-rolls and gears operating them.

The particular features in which my invention consists will be pointed out in the claims at the end of this specification.

40 Figure 1 is a side elevation, partially broken out, of a spindle embodying my invention, it being detached from the machine. Fig. 2 shows the threaded inside of the nut as developed to more clearly show the position or arrangement of the bolt or screw receiving holes therein, and Figs. 3 and 4 details to clearly show the construction of my improved 45 journal-bearing.

45 The spindle a , having the enlargement a' , the feed-rolls a^2 (see Fig. 4) and gears a^3 to rotate them, the slide a^4 , to drive said gears, and provided with screw-threads a^5 , to be engaged by the threaded sleeve a^6 , the loose collar a^7 , and nut a^8 , are all substantially as in my reissue patent referred to. The loose collar a^7 in practice is connected to the operating mechanism (not shown, but substantially such as shown in the patent referred to) by which the slide a^4 is reciprocated. After considerable use the collar a^7 becomes worn, thereby giving rise to lost motion between the said collar and flange b on the sleeve, and also 50 between the said collar and nut a^8 .

55 To take up the wear referred to, the nut a^8 is provided with a series of holes, b' , drilled in line with or so as to follow a single-pitch thread, as b^2 , on the inner side of the said 60 nut. Each hole in the nut in turn registers with a hole in the sleeve a^6 , and the said nut and sleeve are united, as shown, by a bolt or screw, b^3 . It will thus be seen that as the 65 collar becomes worn the nut a^8 may be partially rotated or turned so as to force the said collar against the flange and take up the wear, the partial rotation of the said nut bringing another hole, b' , in line with the hole in the sleeve.

70 Another feature of my invention consists

in providing the spindle with bearings c (see Fig. 3) for the journals of the feed-rolls, gears, &c., the said bearings being constructed as will be described, whereby they may be secured firmly in place without screws and similar devices.

The recess in the journal-box for each bearing c is made greater than a semicircle—that is, the top or upper face, as c' , of the journal-box is above or to one side of the center, as c^2 , from which the said recess was struck. The bearing c has its inner or journal-receiving face, c^3 , in the arc of a circle having its center as at c^4 , the said center being in line with the top or upper face, c' , of the journal-box. It will thus be seen that the outer and inner faces of the bearing are struck from two different centers, as c^2 c^4 , and therefore the bearing is thickest and strongest at its bottom, as clearly shown in Fig. 3.

The bearing c is prevented from being raised or moved bodily from its seat by reason of its being more than a semicircle.

To prevent lateral displacement the bearing on its opposite sides is provided, as herein shown, with flanges c^5 , (see Fig. 1 and dotted lines, Fig. 3,) having their outer edge in the arc of a circle struck from the center c^2 , the said flanges being preferably cast integral with the bearing; but I do not desire to limit myself to this particular means for preventing lateral movement, as other means

may be employed—as, for instance, the outer surface of the bearing may be provided with one or more ribs or projections to enter corresponding grooves in the recess of the journal-box.

The bearing herein shown is not herein claimed, broadly, as it forms the subject-matter of another application, Serial No. 272,819, filed April 30, 1888.

I claim—

1. A wire-carrying spindle having feed-rolls, a sliding segment, a^1 , to operate them, and provided with screw-threads a^5 , and a threaded sleeve to engage the screw-threads a^5 , combined with a threaded nut, as a^8 , having a series of adjusting-holes, b' , arranged in line with or so as to follow the pitch of a thread of the said nut, and with means to secure said nut in adjusted position, substantially as described.

2. The combination, with the sleeve a^6 , provided with a bolt-receiving hole, of a nut, as a^8 , having a series of adjusting-holes, b' , arranged in line with or so as to follow the pitch of a thread of the said nut, and with a bolt or screw to secure the said nut and sleeve, substantially as described.

In testimony whereof I have signed my name to this specification in the presence of two subscribing witnesses:

LOUIS GODDU.
